DESIGN FOR A PHOTOGRAPH ALBUM PAGE OR SIMILAR ARTICLE

Carl Pollak, Forest Hills, N. Y.

Application September 28, 1943, Serial No. 111,225

Term of patent 14 years

(Cl. D61—1)

To all whom it may concern:

Be it known that I, Carl Pollak, a citizen of the United States and a resident of Forest Hills, in the county of Queens, city and State of New York, have invented a new, original, and ornamental Design for a Photograph Album Page or Similar Article, of which the following is a specification, reference being had to the accompanying drawing, forming a part thereof, in which

Fig. 2 is a section on the line 2—2 of Fig. 1.

I claim:

The ornamental design for a photograph album page or similar article, as shown.

CARL POLLAK.
